UNITED STATES PATENT OFFICE.

FRANCIS E. CRAWFORD, OF CANON CITY, COLORADO.

LOCK.

1,190,985.

Specification of Letters Patent. Patented July 11, 1916.

Application filed December 12, 1914. Serial No. 876,959.

To all whom it may concern:

Be it known that I, FRANCIS E. CRAWFORD, a citizen of the United States, residing at Canon City, in the county of Fremont and State of Colorado, have invented new and useful Improvements in Locks, of which the following is a specification.

The present invention relates to devices for protecting the surreptitious opening of a pay station telephone box by unauthorized persons.

In carrying out my invention it is my purpose to construct a simple and effective means which will co-act with the locking bolt of a coin tray or compartment upon a pay station telephone so that the said compartment cannot be opened even by persons having a key which will fit the lock.

For a comprehensive understanding of the invention, reference is to be had to the following description and to the drawings accompanying the description and forming a part of the specification.

In the drawing:—Figure 1 is a perspective view of an ordinary pay station telephone provided with my improvement, Fig. 2 is a vertical transverse section approximately on the line 2—2 of Fig. 1, showing the means whereby the locking bolt of the coin tray is sustained in unlocking position, Fig. 3 is a similar view but illustrating the upper unit or member of the box moved to permit of the opening of the coin compartment or the withdrawal of the coin tray, and Fig. 4 is a detail sectional view approximately on the line 4—4 of Fig. 2.

Referring now to the drawing in detail, the numeral 1 designates an ordinary pay station telephone. As the details of construction of the telephone do not fall within the scope of the present invention, it is not deemed necessary to refer to or to illustrate the particular arrangement of the same, it being merely necessary to set forth that the telephone embodies an upper compartment 2 having chutes through which the coins are inserted and a lower compartment 3 which receives the said coins. If desired the lower compartment may be provided with a slidable door or the same may be provided with a hinged door, in either instance, a lock 3' is provided, the locking bolt 10 being normally forced against a suitable lug or against the upper and outer face of the compartment 2 to prevent the

withdrawal of the door or the opening of the door. The lower compartment has its upper and outer corners provided with lugs 5 through which are passed pivots 6 to 60 secure the upper compartment 2 to the said lower compartment, and the upper compartment 2 is provided with a suitable lock for sustaining the same against opening. The compartment 3 is provided with an 65 elongated slot 6', and the upper compartment 2 is provided upon its outer face at its central portion with a depending member 7 which passes through the slot 6' in the compartment 3. The member 7 has its end 70 provided with an angular extension forming an angular finger 8, and this hook is adapted to pass through an opening in the bolt 10 of the lock 3' to prevent the withdrawal of the bolt even when a key is inserted therein.

To open the compartment 3 it will be necessary to operate the lock of the compartment 2, when the said compartment 2 may be swung to the position illustrated in 80 Fig. 3 of the drawings, thus bringing the finger 8 out of engagement with the opening 9 in the locking bolt 10 to permit of the operation of the said locking bolt. When the sliding bolt 10 is again moved to its 85 locking position, the section 2 is again swung closed upon the section 3, and the finger 8 again enters the slot or opening 9 in the bolt 10, thus securing the bolt against being tampered with by unauthorized persons. 90

From the above description, taken in connection with the accompanying drawing, the simplicity of the device, as well as the advantage thereof will, it is thought, be perfectly apparent to those skilled in the art 95 to which such invention appertains without further detailed description.

Having thus described the invention, what I claim is:

1. A box comprising upper and lower 100 members having a pivoted connection, a lock for the upper member, a door for the lower member, a lock for the said door, the locking bolt of the said last-mentioned lock having an opening, the pivoted upper member being provided with a hook which is adapted to engage with the opening when the members are swung one over and in contact with the other. 105

2. A box comprising an upper and lower 110 section having a pivotal connection, a lock for the upper section, a movable member in

the lower section, a lock for said movable member, the bolt of said lock being provided with an opening and the said bolt when in locking position adapted to contact with the lower section to prevent the sliding of the movable element from the said section, the upper section having an angular finger member passing through an opening in the lower section and adapted

to be received in the opening of the bolt 10 when the said upper section is closed and locked on the lower section.

In testimony whereof I affix my signature in presence of two witnesses.

FRANCIS E. CRAWFORD.
